SUCTION TUBE FILLING END TRAP FOR LOOMS

Clarence N. Coley, Star Rte., Kernersville, N.C.

Filed Apr. 8, 1958, Ser. No. 727,110

11 Claims. (Cl. 139—256)

The present invention relates to weft thread removing devices for automatic looms and relates more particularly to pneumatic weft thread extractors having auxiliary operable means for entrapment of the filling end that is left remaining by an ejected bobbin at the time of bobbin transfer.

Although pneumatic filling end removal or thread extractor devices have been employed in weft replenishing looms and are well known in the art, as exemplified particularly by U.S. Patent Nos.: 2,194,531; 2,219,760; 2,336,320; 2,400,963; and 2,482,691, among many others, the attention for improvement in this particular field has been directed to modifying the suction nozzle or the configuration of the nozzle at the position of filling end contact to facilitate the pick-up of the filling end left by the ejected or expended bobbin. Accidental clogging of an accumulator in the vacuum system or failure of the vacuum system to function properly or lack of adjustment to the linkages which operate the pneumatic nozzle will prevent the extractor from functioning properly to remove the filling end out of the path of travel of the shuttle. Furthermore, particularly with sleazy threads of nylon and the like, as well as coarse threads used particularly for upholstering fabrics, the suction effect may be inadequate to withdraw the thread ends from the nozzle once collected thereat. In some instances where nylon thread is being woven into fabric, there is an increased tendency for the thread to adhere or cling to the surrounding surfaces due to the affinity of nylon for dielectric materials thereby making the suction inadequate to retain and draw the thread out of the way of the shuttle.

Therefore, it is within the contemplation of this invention to provide a combination pneumatic and mechanical thread extractor for positively removing filling ends out of the path of travel of the shuttle in order to eliminate filling ends from being accidentally woven into the fabric.

Another object of this invention is to provide a pneumatic filling end removal apparatus having in juxtaposition to the intake end of a nozzle a sequentially operated means for entrapping a weft end and retaining the end for one or more sequences of weft end removals.

Still another objective of this invention is the provision of a pneumatic weft end extractor and a trap wherein upon failure of an induced air current to withdraw a weft end from the path of travel of the shuttle means is provided to elevate and retain the weft end.

Yet a further objective of this invention is to provide a weft end extractor in which the extractor in the elevated closed extractor condition will retain a thread end removed from the path of travel of the shuttle to eliminate being woven into a fabric.

A further objective of this invention is to provide a plunger mechanism for use in conjunction with the pneumatic thread extractor in which a weft end initially introduced into the nozzle of the extractor will be trapped therein despite failure of the suction system to remove the thread completely after severance.

This invention broadly contemplates that during the time that the shuttle in an automatic loom is in the drive end box and the transfer hammer is pressing a full bobbin into place in the shuttle, the filling end remover having a suction nozzle and trap will dip down from an inoperative position to pick-up a thread from an expended bobbin. This thread, when suction is available, will be

2

held by suction in an extractor, until severed of after severance by the selvage thread cutter. Although suction may be available an auxiliary mechanical means is provided to retain the thread end which will be severed and will ultimately either be drawn into the pneumatic nozzle orifice by induced air currents or be retained by means of the auxiliary mechanical means for subsequent removal by an operator.

Other objectives and many of the attendant advantages of this invention relating to a thread extractor for looms will become more readily apparent from the following detailed description taken in conjunction with the accompanying drawing in which like characters of reference designate corresponding parts throughout the several views, and wherein:

FIG. 1 is a plan view of the forward section only of one end of a lay illustrating a preferred embodiment of this invention mounted on a loom;

FIG. 2 is an enlarged perspective view of the pneumatic extractor assemblage and mounting with the unit being illustrated in the upward or closed position;

FIG. 3 is an end elevational view of the pneumatic weft thread extractor in the lowered position for a filling end pick-up;

FIG. 4 is an end elevational view, similar to FIG. 3, with the extractor mechanism in the elevated position relative to the lay plush, with the weft trap in the closed position;

FIG. 5 is an enlarged partial transverse sectional view taken substantially along the plane of section line 5—5 of FIG. 4; and

FIG. 6 is an enlarged partial end elevational view of the reverse side of the suction tube mounting bracket from the weft plunger device shown in FIGS. 3 and 4.

Referring to the drawing and particularly to FIG. 1 there is shown therein a loom frame 10 on which is supported a bracket 11 for retaining a conventional bobbin magazine (not shown) that may be pivoted to introduce a full bobbin into position. A transfer arm 13, only a portion of which is shown, is pivotally mounted on the stud 14 as in a Crompton and Knowles loom S-6. The loom lay 16 will reciprocate backwardly and forwardly in a conventional manner through known means with the loom having a shuttle box 17 at one end of the lay to receive the shuttle 18 on alternate flights. A bobbin 19 is releasably contained within the shuttle 18 and upon depletion of the thread 20 wound on the bobbin, the spent bobbin will be discharged through conventional means from the shuttle upon introduction of the full bobbin from the magazine by means of a conventional replenishing system, not shown. Replenishing of a full bobbin usually occurs when the lay is situated at the front center and the shuttle is in the drive end box. In this replenishing position, a filling end extractor attachment 21 will dip downwardly to pick-up a thread end 22 which has been severed by means of a standard thread cutting attachment (not shown) from the expended bobbin which thread end extends from the selvage 23 of the fabric 24 adjacent to the temple roll housing 25 to which housing a temple cutter 28 is affixed in order to sever weft ends adjacent to the selvage.

The thread end 22 will reach from the selvage 23 to the bobbin 19 in the lay and box across and over the plush pad 27 which pad is usually located slightly below the shuttle path of travel between the shuttle box and the woven fabric. Directly in line with the pad 27 and to the right, in FIG. 1, is the weft or filling end extractor attachment 21.

The loom is also provided with a conventional thread cutter, not shown, which cutter upon presentation of a weft end during the replenishing operation will operate to sever the filling end that extends from the shuttle adja-

cent to the shuttle eye, all of which is conventional and does not constitute a part of this invention.

In the embodiment shown the filling end extractor 21 is supported on the stand 29 which stand has a level reset shoulder 30 and laterally spaced inwardly projecting lugs 31 through which lugs a supporting rod 32 is slidably retained with a limit collar 33 mounted thereon. A compression spring 34 encircles the supporting rod 32 forward of the lug 31 to resiliently urge the rod to the left in FIGS. 3 and 4. A fin or filling guide 35 in the form of a flat triangular plate is securely fastened as by welding or other suitable means to the bifurcated end 37 of the supporting rod 32. It is intended that the lower edge 38 of the filling guide 35 will be parallel to the plane of the plush pad 27 during the pick-up operation, as clearly illustrated in FIG. 3.

The compression spring 34 on the supporting rod 32 will urge the suction nozzle outwardly so that the collar 33 will shoulder against the left lug 31. In the event the shuttle 18 should strike the nozzle, the filling end extractor will be deflected to the right or backwards as the spring is compressed sufficiently to remove the nozzle out of the path of shuttle travel.

A nozzle 39 having a converging mouth 40 is securely fastened to the filling guide with the mouth 40 of the nozzle terminating slightly above the lower edge 38 of the guide 35. The terminal portion of the nozzle is provided with a tongue-like guide or thread presenter 41 which guide has a return bend 42 to introduce and guide loose weft thread ends into the mouth of the nozzle. Various types of nozzles have been utilized to accomplish the objective of this invention and per se do not constitute a part of this invention.

A flexible hose connector 43 is fastened to the upper end of the suction tube 44 for connection to a suction pump 45, schematically shown, which pump is adequate to generate a flow or current of air into the mouth of the nozzle thereby inducing a thread end to flow into the nozzle mouth. An accumulator, not shown, for collecting filling ends may be installed in the suction line, at an appropriate location, within which accumulator the filling ends are deposited for subsequent removal. Frequently, the accumulator becomes full and unless emptied the flow of air therethrough may be impaired thus restricting the collection of loose ends which will remain in the lay for accidental displacement back into the selvage. This is commonly referred to as " jerked-in filling."

The transferer arm stud 14 supporting the transferer arm 13 terminates at one end in the stand to retain a flat friction spring 25 through the lock nut 46 which spring 25 maintains the filling end removal apparatus 21 in the normal running or up position. Transferer arm 13 is normally provided with a stud which extends laterally from the arm to engage with the stand 29 such as to be reset to shoulder 30 or other suitable location on the stand. Upon downward displacement of the transferer arm the stud will engage with the stand and move the stand from the normal raised position, as shown in FIG. 4, to the lowered position, as shown in FIG. 3. Subsequently, near the completion of the backward stroke of the lay, following the transfer operation and the weft removal, the reset rod 47, through conventional means, will be elevated to engage with the reset shoulder 30 thereby raising the stand to the inoperative position preparatory for another cycle.

Cam 48 for adjusting the position of the nozzle and the filling guide relative to the plush pad 27 is eccentrically mounted on the shaft 49 and secured in position by the nut 50 which threadably engages the end of the shaft.

The disclosure thus far has substantially disclosed with the exception of the entrapment mechanism, the prior art as embodied in one type of loom such as the Crompton and Knowles S-6 loom.

The attachment constituting one embodiment of this invention is illustrated in combination with the suction nozzle 39 in FIGS. 3 and 4, particularly, wherein the ex-

tractor trap plunger mechanism 51 has a cylindrical housing 52 that is mounted by means of a plate 53 to which the housing is fastened as by welding or other suitable means, by bolts 54, to one side of the filling guide 35.

5 The lower conically-shaped portion 55 of the housing is positioned adjacent to the entrance or mouth of the nozzle and has an axial bore 56 therethrough which communicates with an enlarged axial chamber 57 in the cylindrical housing 52.

10 A knurled closure cap 58 threadably engages the upper end of the housing 52 and has an axial bore 59 therethrough in alignment with the bore 55 and chamber 56. A plunger 60 extends axially through the plunger housing members and has retained thereon and within the housing 15 chamber a compression spring 61 and a limit collar 62 which collar will normally be in the lower or extended condition as when the plunger is ejected or protruded from the housing. In the normal protruded or inoperative position, the plunger end 63 will be projected outwardly from 20 the lower portion of the housing in order to engage or make point contact with the top surface of the presenter or thread-guide tongue 41, as more clearly shown in FIGS. 4 and 6.

The other end 64 of the plunger rod 60 has an opening 65 therein to receive a fastening ring 66. A flexible connector 67, such as a link chain or other suitable lanyard, is fastened to the ring 66 at one end of the connector and the other end of the connector is fastened to a stationary part of the loom frame designated schematically as 68. The linear length of the flexible connector 67 is determined primarily by the desired action of the plunger so that upon presentation of the nozzle and thread presenter to the plush pad during transfer, that is, when the nozzle is introduced to the plush pad in the suction 35 pick-up stage, the plunger will be retracted sufficiently into the plunger housing to provide a gap 69 between the end of the plunger and the top surface of the presenter thereby permitting and enabling the thread guide to pick-up the weft thread on the upper surface of the presenter 40 with the aid or without the aid of suction from the pump. Obviously, the space or gap 69 provided between the end of the plunger and the top of the presenter will be governed by the type of thread, the timing of the suction intake, and the type of thread guide employed. As illustrated in FIG. 3, the end of the plunger is retracted from 45 the presenter and the connector does not have any slack as distinguished from FIG. 4 in which the plunger is projected to illustrate a thread end that is trapped on the presenter although this is normally the commencement of another cycle.

50 In normal operation the thread extractor will be introduced to the plush pad with the plunger 60 being retracted as in FIG. 3. The filling guide lower edge 38 will provide adequate friction on the weft end to present it to the guide tongue wherein an induced current of air 55 will cause the severed thread end to be introduced into the mouth of the nozzle for deposition in the nozzle and withdraw through the hose 43 into an accumulator. However, frequently either by failure of the suction, the 60 thread weight, or faulty air, the thread end will be picked up by the presenter but will fall back down in the lay to be jerked-in the cloth on the next flight of the shuttle. By trapping the thread end, without clamping, on the presenter, enables the suction to more effectively remove the 65 loose weft end positioned on the presenter. However, in the event the suction fails to function properly, when the lay is displaced away from the extractor, the entrapped weft end will be left dangling from the presenter and, having been cut at both ends, it will fall by gravity to the 70 floor or out of the shuttle path. The effectiveness of this entrapping auxiliary attachment is used to greater advantage without having the plunger close the entire mouth of the nozzle or restrict the flow of air into the mouth of the nozzle.

75 It has been found also that this attachment is capable

of removing more than one end in those instances where-
in more than one filling end is in the lay. Also, when
the system completely fails, this attachment in combina-
tion with the presenter, functions as a fully mechanical
unit discharging the weft ends out of the lay in close
proximity thereof for subsequent removal.

Obviously, many modifications and variations may be
made in the construction and arrangement of the plunger,
the nozzle and presenter, as well as the means for pro-
jecting the entrapment mechanism in the light of the
above teachings without departing from the real spirit
and purpose of the invention. It is, therefore, to be
understood that within the scope of the appended claims
many modified forms of structure as well as the use of
mechanical equivalents may be reasonably included and
modifications are contemplated.

What is claimed is:

1. In a weft replenishing loom having a backwardly
and forwardly reciprocating lay provided with a shuttle
box containing a shuttle from which a thread extends
to the adjacent selvage, a pneumatic weft end extractor
movable from an elevated to a pick-up position, said
extractor having a nozzle and a guide tongue in spaced
relation thereto, suction means to induce the flow of air
into said nozzle, a displaceable member supported for
reciprocation in juxtaposition to said nozzle, said member
being normally urged to contact the guide tongue to
removably support an extracted thread thereon, and
means to withdraw said member away from said guide
tongue in the extractor pick-up position whereby said
suction flow of air will remove an extracted thread sup-
ported on the guide tongue.

2. In a weft replenishing loom having a backwardly
and forwardly reciprocating lay provided with a shuttle
box containing a shuttle from which a thread extends to
the adjacent selvage, a pneumatic weft end extractor
having a nozzle, said extractor having a thread guide
tongue extending at the terminal end of the nozzle, means
to induce a suction into said nozzle, a plunger rod sup-
ported in juxtaposition to said nozzle, said rod being
normally urged to contact the guide tongue to removably
support a thread end thereon, and means to withdraw said
rod from said guide tongue to introduce a weft onto the
tongue and into the nozzle.

3. In a weft replenishing loom having a backwardly
and forwardly reciprocating lay provided with a shuttle
box containing a shuttle from which a thread extends to
the adjacent selvage, a pneumatic weft end extractor
movable from an elevated to a weft pick-up position, said
extractor having a nozzle, said extractor having a thread
supporting means thereon projecting beyond and in spaced
relationship to said nozzle, a plunger rod supported in
juxtaposition to said nozzle, said rod being normally
urged to contact the thread supporting means to removably
support a thread end thereon, and means to withdraw said
rod from said thread supporting means in the extractor
weft pick-up position.

4. A weft extractor for weft replenishing looms having
a lay provided with a shuttle box from which a thread ex-
tends to the adjacent selvage, said extractor comprising a
member having an arcuate thread guide tongue thereon,
and a reciprocable plunger mounted in juxtaposition to
said member to cooperatively engage with the guide
tongue to removably support a yarn on said guide tongue.

5. In a weft replenishing loom having a lay and shuttle
box into which a thread extends from the cloth selvage,
a pneumatic weft extractor nozzle, means to induce a
flow of air into said nozzle, said nozzle having an arcuate
thread pick-up tongue thereon, mechanical reciprocating
means for engaging the tongue and removably support-
ing a thread engaged on the thread pick-up tongue.

6. In a weft replenishing loom having a lay and shuttle
box into which a thread extends from the cloth selvage,
a weft extractor member, said member having an arcuate
thread pick-up tongue thereon, plunger means on said
member for removably supporting said thread end when
it is engaged on the tongue of said member to displace
said thread end.

7. An attachment for a pneumatic thread extractor for
weft replenishing looms, said extractor being movable
from inoperative to operative positions and having a
nozzle and an arcuate thread presenter projecting from
the extractor in spaced fixed relation to said nozzle, said
attachment comprising a spring biased plunger means
mounted in juxtaposition to said nozzle operable from an
inoperative to an operative position to removably sup-
port a weft end on the presenter in the inoperative
position.

8. In a weft replenishing loom having a lay and a
shuttle box to which a thread extends from the cloth
selvage, a pneumatic thread extractor having an arcuate
protruding tongue and nozzle associated therewith, means
to induce a current of air into said nozzle, and reciprocable
plunger means for releasably supporting a thread end in
the path of said induced air currents on said tongue
leaving the nozzle substantially open.

9. In a weft replenishing loom having a lay and a
shuttle box to which a thread extends from the cloth
selvage, a pneumatic thread extractor having a nozzle,
means to induce a current of air into said nozzle, and a
reciprocable plunger means extending across and in
spaced relation to said nozzle to removably support a
thread on said extractor upon displacement of the extrac-
tor relative to the lay leaving the nozzle substantially
open.

35 10. In a weft replenishing loom having a lay and
shuttle box into which a thread extends from the cloth
selvage, a weft extractor member, said member having
an arcuate thread pick-up tongue for supporting a thread
thereon, said weft extractor member being movable from
an elevated to a thread pick-up position, a plunger for
normally communicating with the tongue in the extractor
elevated position, and means for withdrawing the plunger
from communication with the tongue at least in the ex-
tractor thread pick-up position.

45 11. In a weft thread replenishing loom having a lay
with a shuttle box thereon containing a shuttle, and where-
in a weft thread extends from said shuttle to the adjac-
ent selvage, a substantially vertical tubular weft extract-
ing device movable on weft replenishment from a nor-
mally inactive position to an active position, said tubular
device terminating in a mouth at one end thereof with
a portion of said tubular device extending beyond said
mouth and serving to guide said extended thread into said
mouth upon movement of said device to the active posi-
tion, means to create suction at said mouth, spring loaded
means extending substantially longitudinally of said tubu-
lar device and normally biased to engage said extended
portion to trap said extended thread in said mouth, and
means effective upon movement of said device to the
active position to disengage said spring loaded means
from said extended portion to permit entry of said ex-
tended thread into said mouth.
